DOUBLE-ACTING BENCH PLANE

Ray K. Bryant, Liberty, S. C.

Application June 6, 1950, Serial No. 166,365

6 Claims. (Cl. 145—5)

1

This invention relates to a double acting bench plane which cuts on the rearward or retracting stroke as well as on the forward stroke, the primary object of the invention being to provide a practical and efficient bench plane of this character which is of simple and rugged construction.

Another important object of the invention is to provide a double acting bench plane of the character indicated above which involves a dual cutter arrangement in which the blades or cutter bits are individually and removably mounted in a holder but are capable of adjustment together toward and away from the under side of the stock by vertical adjustment of the holder, the blades being oppositely angulated in the holder, and the holder being automatically rockable as the plane is moved forwardly or rearwardly in contact with the work to present the proper blade in cutting position.

Other important objects and advantageous features of the invention will be apparent from the following description and the accompanying drawings, wherein, merely for illustrative purposes, a specific embodiment of the invention is set forth in detail.

In the drawings, wherein like numerals designate like parts throughout the several views:

Figure 1 is a fragmentary top plan view, partly broken away;

Figure 2 is a vertically contracted left hand side elevation, partly broken away, showing the cutter assembly in intermediate or neutral position;

Figure 3 is a transverse vertical section, taken on the line 3—3 of Figure 2;

Figure 4 is a general fragmentary vertical longitudinal section showing the cutter assembly in position for cutting the work on a rearward or retracting stroke of the plane;

Figure 5 is a transverse vertical section taken on the line 5—5 of Figure 2;

Figure 6 is a view similar to Figure 4, showing in dotted lines an upward adjustment of the cutter assembly; and

Figure 7 is a perspective view of the mechanism including the cutter assembly, removed from the plane stock.

Referring in detail to the drawings, the numeral 9 generally designates the plane stock having a bottom plate 10 adapted to be slid along the work 11, such as a board supported upon a bench (not shown), longitudinal side walls 12 tapered upwardly from the opposite ends 13 and 14, respectively, of the stock to the risers 15 at the middle of the stock. A central horizontal cross member or plate 16 extends across the stock be-

2

tween the risers 15. Another cross member 17, including a boss 18, extends between the side walls 12 near the end 13 of the stock, while a rear cross member 19 extends between risers 20 near the end 14 of the stock. A generally conventional knob handle 21 involves a mounting screw 22 projecting from its lower end to thread into a hole 24 located centrally in the bar or plate 16. The bottom plate 10 of the stock 9 has a transversely elongated opening 25 positioned in vertical alignment with the central cross member through which the cutter blades or bits operate upon the work 11.

Vertically elongated slots 26 are formed in the stock side walls 12 and extend in a plane perpendicular to the stock bottom plate 10 and passing midway between the front and rear edges 27 and 28, respectively, of the opening 25, the slots having their lower ends 29 spaced upwardly from the stock bottom plate 10 with their upper ends 30 terminating in the risers 15, as shown in Figure 3. The slots 26 accommodate a spindle 31 whose opposite ends project outwardly beyond the side walls 12 and engage in holes 32 in the lower ends 29 of legs 33 positioned at the outer sides of the side walls 12 and depending from the bight portion 33 of an inverted U-shaped adjusting yoke 34. The bight portion 33 is substantially spaced above and parallelly overlies the central cross member 16. A vertical adjusting screw 35, having a knob 36 on its upper end, is threaded downwardly through the middle of the yoke bight portion 33 with its lower end 37 engaged with the stock cross member 16. A smaller assembling screw 38, having a head 39 on its lower end is threaded upwardly through the cross member 16 and into a bore 40 in the lower end of the adjusting screw 35. By this means rotation of the adjusting screw 35 in opposite directions raises and lowers the yoke 34 and the spindle 31 and the two similar jaws or holder plates 41.

As shown in Figures 4, 6 and 7, the holder plates 41 are relatively thick and segmental in shape, and have downwardly converging ends 42, a straight lower edge 43, and a curved upper edge 44, and have centered transverse holes 45 receiving opposite end portions of the spindle 31. The holder plates, as shown in Figure 3, are positioned against the inward sides of the stock side walls 12. Near their upper edges 44 the plates 41 have sockets 46 positioned at their vertical centers.

Opening through opposite ends of the lower edges 43 of the holder plates 41 are blade or bit slots 47 which are parallel to the adjacent converging ends 42 of the plates, and in these slots

are inserted the upper plain portions 48 of the transversely elongated rectangular, front and rear blades or bits 49 and 50, respectively. The blades have straight upper edges 51 and lower cutting edges 52 parallel thereto. The cutting edges 52 are defined by tapering the outer sides of the blades from the lower end of the plain portions 48 to the lower ends of the blades, as indicated at 48', whereby the cutting actions of the blades 49 and 50 are opposite. The blades are cut away at their ends at 51' to shorten the portion 48' to fit the opening 25. Set screws 52' are threaded through the ends 42 of the plates 41 to engage and lock the blades in the slots 47 with the tapered lower portions of the blades projecting below the lower edges 43 of the plates 41.

A transversely elongated shaving guide block 53 of wedge cross section is positioned between the blade holder plates 41 and between the blades 49 and 50 to guide the shavings or chips upward as they are cut. The block 53 has plain ends 54 which are engaged with the inner sides of the plates 41 and has a longitudinal bore 55 extending therethrough midway between its upper and lower ends 56 and 57, respectively, through which the spindle 31 extends to hold the block 53 in place. As shown in Figure 4, the upper and wider end 56 of the block 53 is rounded as is the lower and narrower end 57 thereof.

The upper ends of the block ends 54 are recessed, as indicated at 58, and a longitudinal bore 59 formed through the upper part of the block 53 accommodates a second spindle 60 which has end portions extending across the recesses 58 and terminating in rounded ends 61 positioned in the conformably shaped sockets 46 in the inward sides of the blade holder plates 41 near their upper edges 44, whereby the blade holder plates 41 are connected with the shaving guide block 53 for rotation together on the spindle 31. As shown in Figure 4, the shaving guide block 53 is centered between the blades 49 and 50, with its rounded lower edge 57 vertically spaced at a substantial distance above the cutting edges 52 of the blades.

Journalized on the upper spindle 60 in the spaces provided by the recesses 58 between the ends of the shaving guide block 53 and the blade holder plates 41 are eyes 64 of rounded cross section which are on the ends of horizontal arms 62. The arms 62 converge toward their opposite ends and are joined by a portion 63 to form a yoke 64. The portion 63 is slotted in its free end to define two spaced arms 63' traversed by a pivot bolt 65. A vertical lever 66, has an upper end portion 67 traversed by a pivot bolt 68 extending through transversely spaced ears 69 rising from the stock cross member 19 through a slot 70 formed in the cross member 19 between these ears, as shown in Figure 5. An upwardly curved handle 71 is fixed at its lower end to the upper end portion 67 of the lever 66. The lever 66 has a lower end portion 72 which curves downwardly toward the end 14 of the stock and is traversed by the pivot bolt 65, the pivot bolt 65 being displaced toward the stock end 14 off-center from the pivot bolt 68 in the intermediate neutral perpendicular position of the handle 71 shown in Figures 2 and 6. The slot 70 in the stock cross member 19 is of such a length and so positioned that in opposite tilting movements of the handle 71 on the pivot bolt 65 the upper portion 67 of the lever 66 engages opposite ends of the slot 70 whereby rocking of the blade holder plates in opposite directions is limited to give the cutter blades 49 and 50 correctly angulated cutting positions.

It will be obvious from the foregoing that with the blades adjusted for cutting depth by means of the adjusting screw 35 and with the bottom plate 18 of the stock 9 applied to plane a surface of the work 11, a push in one direction on the handle 71 will tilt the handle 71 in a corresponding direction from the neutral position. This pulls the yoke 64 in the opposite direction and tilts the blade holder plates 41 in the same direction, thereby elevating the blade 49 above the stock bottom plate 18 and depressing the blade 50 through the opening 25 in the bottom plate 18 into contact with the work at a proper declining angle for cutting or planing in said one direction. If at the end of such a stroke an opposite pull is exerted on the handle 71 for a return stroke, the yoke 64 is pushed in the opposite direction so as to tilt the blade holder plates 41 in said opposite direction, withdraw the blade 49 from cutting position and depress the blade 50 through the stock bottom plate opening 18 into correctly declining cutting relation to the work 11, as shown in Figure 4. As strokes are made in opposite directions with the plane these changes in the cutting relations of the blades 49 and 50 take place instantly and automatically.

What is claimed is:

1. In a double acting plane, a plane stock having a work engaging face, a blade holder pivoted on said stock on an axis extending transversely of said stock, said blade having a neutral position, a pair of blades depending from said blade holder, said blades converging downwardly toward each other with their lower edges located above the work engaging face of said stock in the neutral position of said blade holder, said blade holder being arranged to be pivoted in opposite directions away from its neutral position so as to project one of said blades at a time downwardly below the work engaging face of the stock at a declining angle to contact a surface to be planed while the other blade remains above the work engaging face of the stock, a vertical hand lever pivoted on said stock on a horizontal axis extending transversely of said stock, said hand lever having an intermediate position, and means operatively connecting said hand lever to said blade holder whereby said blade holder is pivoted in opposite directions from its neutral position as manual pressure is applied to said hand lever to move the plane stock in opposite directions in contact with the work.

2. In a double acting bench plane, a plane stock having a plane bottom plate and side walls thereon, a pair of end cross members extending between said side walls above said bottom plate, an intermediate cross member extending between said side walls and spaced from said end cross members, said bottom plate being formed with a blade exposing opening beneath said intermediate cross member, a blade holder positioned between said side walls and between said intermediate cross member and said bottom plate, means mounting said blade holder in place, said blade holder having a neutral position and being arranged to tilt toward opposite ends of the stock from the neutral position, a pair of spaced and downwardly converging blades mounted on said blade holder having cutting edges depending below said holder, said cutting edges being spaced above said bottom plate in the neutral position of the blade holder, a vertical handle projecting above one of said end cross members, a vertical lever secured to depend from the lower end of said handle, means pivoting said lever on said one

end cross member to swing on an axis extending transversely of said stock, and a yoke extending between and pivotally connected to said vertical lever and to said blade holder whereby application of pressures on said handle in opposite directions produces strokes of the plane and swinging of said handle in corresponding directions and tilting of said blade holder in the opposite directions from its neutral position so as to depress one of said blades at a time into operative position through said blade opening at declining angles.

3. In a double acting plane, a plane stock having a bottom plate, said bottom plate being formed with a blade opening longitudinally spaced from the ends of the stock, a blade holder pivoted on said stock above said blade opening on a horizontal axis extending across said stock, said blade holder having a perpendicular neutral position, a pair of longitudinally spaced blades depending from said blade holder, said blades converging downwardly toward each other with their lower edges located above said bottom plate in the neutral position of said blade holder, said blades being arranged to alternately project downwardly through said blade opening at a declining angle to contact a surface to be planed as said blade holder is tilted in opposite directions from its neutral position, a vertical hand lever pivoted on said stock to swing toward opposite ends of said stock, said hand lever having an intermediate position, and means operatively connecting said hand lever to said blade holder whereby said blade holder is tilted in opposite directions away from its neutral position as manual pressure is applied to swing said hand lever in opposite directions and to move the plane in corresponding directions in contact with the surface to be planed, said stock having laterally spaced longitudinal side walls rising therefrom and formed with vertically elongated slots in line with said blade opening, a first spindle extending across said stock with its ends in said slots, said spindle traversing said blade holder between said front and rear blades and mounting said blade holder for tilting movement, a cross member extending between said side walls and spaced above said blade holder, a yoke having a portion spaced above said cross member and a leg depending therefrom and connected to said spindle, a vertical adjusting screw threaded through said yoke portion and connected to said blade holder, said adjusting screw being rotatable in opposite directions to raise and lower said blade holder to determine the amount of projection of said blades below the stock plate bottom in their operative positions.

4. In a double acting plane, a plane stock having a bottom plate, said bottom plate being formed with a blade opening longitudinally spaced from the ends of the stock, a blade holder pivoted on said stock above said blade opening on a horizontal axis extending across said stock, said blade holder having a perpendicular neutral position, a pair of longitudinally spaced blades depending from said blade holder, said blades converging downwardly toward each other with their lower edges located above said bottom plate in the neutral position of said blade holder, said blades being arranged to alternately project downwardly through said blade opening at a declining angle to contact a surface to be planed as said blade holder is tilted in opposite directions from its neutral position, a vertical hand lever pivoted on said stock to swing toward opposite

ends of said stock, said hand lever having an intermediate position, and means operatively connecting said hand lever to said blade holder whereby said blade holder is tilted in opposite directions away from its neutral position as manual pressure is applied to swing said hand lever in opposite directions and to move the plane in corresponding directions in contact with the surface to be planed, said stock having laterally spaced longitudinal side walls rising therefrom and formed with vertically elongated slots in line with said blade opening, a first spindle extending across said stock with its ends in said slots, said spindle traversing said blade holder between said front and rear blades and mounting said blade holder for tilting movement, a cross member extending between said side walls and spaced above said blade holder, a yoke having a portion spaced above said cross member and a leg depending therefrom and connected to said spindle, a vertical adjusting screw threaded through said yoke portion and connected to said blade holder, said adjusting screw being rotatable in opposite directions to raise and lower said blade holder to determine the amount of projection of said blades below the stock plate bottom in their operative positions, a shaving guide mounted on said stock and depending between and in spaced relation to said blades for guiding shavings upwardly between the blades and said guide as the shavings are cut by the blades.

5. In a double acting plane, a plane stock having a bottom plate, said bottom plate being formed with a blade opening longitudinally spaced from the ends of the stock, a blade holder pivoted on said stock above said blade opening on a horizontal axis extending across said stock, said blade holder having a perpendicular neutral position, a pair of longitudinally spaced blades depending from said blade holder, said blades converging downwardly toward each other with their lower edges located above said bottom plate in the neutral position of said blade holder, said blades being arranged to alternately project downwardly through said blade opening at a declining angle to contact a surface to be planed as said blade holder is tilted in opposite directions from its neutral position, a vertical hand lever pivoted on said stock to swing toward opposite ends of said stock, said hand lever having an intermediate position, and means operatively connecting said hand lever to said blade holder whereby said blade holder is tilted in opposite directions away from its neutral position as manual pressure is applied to swing said hand lever in opposite directions and to move the plane in corresponding directions in contact with the surface to be planed, said stock having laterally spaced longitudinal side walls rising therefrom and formed with vertically elongated slots in line with said blade opening, a first spindle extending across said stock with its ends in said slots, said spindle traversing said blade holder between said front and rear blades and mounting said blade holder for tilting movement, a cross member extending between said side walls and spaced above said blade holder, a yoke having a portion spaced above said cross member and a leg depending therefrom and connected to said spindle, a vertical adjusting screw threaded through said yoke portion and connected to said blade holder, said adjusting screw being rotatable in opposite directions to raise and lower said blade holder to determine the amount of projection of said blades below the stock plate bottom in their operative

positions, a shaving guide mounted on said stock and depending between and in spaced relation to said blades for guiding shavings upwardly between the blades and said guide as the shavings are cut by the blades, said blade holder comprising a pair of holder plates positioned at opposite sides of said stock with said shaving guide positioned therebetween, said blade holder plates and shaving guide being connected to tilt together.

6. In a double acting plane, a plane stock having a bottom plate, said bottom plate being formed with a blade opening longitudinally spaced from the ends of the stock, a blade holder pivoted on said stock above said blade opening on a horizontal axis extending across said stock, said blade holder having a perpendicular neutral position, a pair of longitudinally spaced blades depending from said blade holder, said blades converging downwardly toward each other with their lower edges located above said bottom plate in the neutral position of said blade holder, said blades being arranged to alternately project downwardly through said blade opening at a declining angle to contact a surface to be planed as said blade holder is tilted in opposite directions from its neutral position, a vertical hand lever pivoted on said stock to swing toward opposite ends of said stock, said hand lever having an intermediate position, and means operatively connecting said hand lever to said blade holder whereby said blade holder is tilted in opposite directions away from its neutral position as manual pressure is applied to swing said hand lever in opposite directions and to move the plane in corresponding directions in contact with the surface to be planed, said stock having

5 laterally spaced longitudinal side walls rising therefrom and formed with vertically elongated slots in line with said blade opening, a first 10 spindle extending across said stock with its ends in said slots, said spindle traversing said blade holder between said front and rear blades and mounting said blade holder for tilting movement, a cross member extending between said side walls and spaced above said blade holder, a yoke having a portion spaced above said cross member and a leg depending therefrom and connected to said spindle, a vertical adjusting screw threaded through said yoke portion and connected to said blade holder, said adjusting screw being rotatable in opposite directions to raise and lower said blade holder to determine the amount of projection of said blades below the stock plate bottom in their operative positions, a shaving guide mounted on said stock and depending between and in spaced relation to said blades for guiding shavings upwardly between the blades and said guide as the shavings are cut by the blades, said blade holder comprising a pair of holder plates positioned at opposite sides of said stock with said shaving guide positioned therebetween, said blade holder plates and shaving guide being connected to tilt together, said holder plates being formed with downwardly converging blade slots opening through their lower ends in which said blades are secured with said blades extending between the holder plates.
